METHOD AND MEANS FOR TAKING CORES

Benjamin W. Sewell, Tulsa, Okla., assignor to
Standard Oil Development Company, a corpora-
tion of Delaware

Application August 16, 1940, Serial No. 352,854

6 Claims. (Cl. 255—72)

The present invention is directed to methods for obtaining cores and to means adapted to be used in said methods.

It has long been conventional to the art of drilling bore holes to obtain cores of the formation being penetrated by the bore hole in order to furnish useful geological information.

In the old and well known means and methods employed in recovering the cores the fluids present in the core under the original formation pressure were not retained, but were largely lost as the core was drawn upwardly to the surface of the earth, and the pressure in the core was gradually diminished.

In an effort to obtain more complete geological data, pressure core barrels have been constructed which seal the core under the pressure of the formation from which it is cut, and the sealed core is withdrawn to the surface of the earth where the retained fluids are released into suitable containers and tested along with the core in an effort to properly evaluate the characteristics of the formation from which the core has been obtained. Pressure core barrels for carrying out the above described procedure are disclosed in my copending applications Ser. Nos. 269,168 and 310,284. Such pressure core barrels, however, suffer from the disadvantage that they must be designed to have considerable mechanical strength in order to withstand the pressure differentials to which they are subjected by the sealed cores. This method of construction not only renders the pressure core barrel very expensive, but also requires that the parts thereof be made so large that the diameter of the core obtained is of relatively small dimensions.

It is an object of the present invention to provide a method of obtaining cores whereby the fluids originally present in the core under formation pressure may be obtained by the operator without the use of a core barrel subjected to high internal pressures.

Another object of the present invention is to provide a core barrel used in a hole filled with drilling fluid whereby the drilling fluid is used to form a liquid seal for the gases and low specific gravity liquids released from the core as it is withdrawn to the surface of the earth so that the amount of gas and low specific gravity liquids released from the core may be determined by an operator.

Other objects and advantages of the present invention may be seen from a reading of the following description taken in conjunction with the accompanying drawings in which:

Fig. 1 is a cross sectional view of one modification of apparatus which may be used for carrying out the present invention;

Fig. 2 is a view of the apparatus appearing in Fig. 1 showing the lower end of the core barrel provided with a means for sealing it in a liquid-tight manner;

Fig. 3 is a fragmental cross sectional view of another modification for carrying out the present invention; and

Fig. 4 is a fragmental cross sectional view of still another modification suitable for carrying out the present invention.

Referring specifically to the drawings and first to the modification shown in Figs. 1 and 2, a core barrel 10 is provided with a tubular body 11 which has interiorly arranged in the lower end thereof a core catcher 12 in the manner generally conventional to the art. The upper end of the core barrel is formed with a head 13 for engagement with a conventional fishing tool which is indicated fragmentally as 14.

At the upper end of cylindrical body 11 is provided a block 15 having a central passage 16 controlled by ball valve 17 and spring 18. The ball valve is arranged in a cavity 19 having access to the exterior through slots 20.

The core barrels illustrated in the drawing are arranged for use with conventional wire line equipment. The diameters of the barrels are proportioned so that they are held in position to take cores by the pressure developed by the drilling fluid circulated during coring. That is to say, when the operator wishes to take a core, he simply drops the core barrel down the drill stem and begins to circulate drilling fluid. The pressure on the barrel forces the core barrel against a seat in the coring bit and drilling is begun in order to obtain a core. This method of using the pressure of drilling fluid to hold a core barrel in position while taking a core is conventional to the art and no novelty is claimed in the use of this particular feature.

The core obtained enters into the cylindrical passage 11. When it is desired to remove the core barrel containing the core from the bit, this is done in the conventional manner. The rotation of the core bit and the circulation of the drilling fluid is stopped and fishing device 14 attached to a wire line is dropped down the drill stem to engage 13. An upward pull on the fishing device then withdraws the core barrel upwardly through the drill stem.

Since it is an object of the invention to retain gas and oil originally present in the core, but

released as the core is withdrawn to the surface, it is desirable to fill the core barrel with liquid before it is inserted in the drill stem so that the only gas present within the core barrel when it is removed from the bore hole will be that released from the core.

As the core is cut and enters the core barrel, excess liquid may pass upwardly through passages 16 and slot 20. It will be evident that when the core is cut the core barrel will be full of liquid typical of that in the bottom of the hole adjacent to the formation and the hard mineral core.

As the core barrel containing a core is withdrawn to the surface of the earth, the pressure on the liquid with which the hole is filled will gradually diminish and allow the pressure on the core to be correspondingly diminished because the lower end of the cylinder 11 is in fluid communication with the liquid in the drill pipe. The release of the pressure in the core will allow gas and oil which were retained by the core under formation pressure to be gradually released. As both the gas and the oil released by the core are of lighter specific gravity than the drilling mud with which the core barrel and drill pipe are filled, they will migrate to the top of the core barrel and cause the drilling mud to be displaced downwardly in the core barrel, the tension on spring 18 being such that the ball 17 seals the passage 16 when there is only a small pressure differential present inside of the barrel.

In carrying out the invention it is necessary that the drill pipe contain fluid to its uppermost portion, and in order to more readily use the modification shown in Figs. 1 and 2 it is preferred to place the enlarged section 22 in the top joint of the drill pipe and to keep the level of the mud within this enlarged section, for example, at point 23, as shown in the drawings.

When the core barrel has been withdrawn so that its upper end is exposed to the atmosphere and its lower end is still within section 22 as illustrated in Fig. 1, a cap 24 is arranged on the lower end of cylindrical portion 11 in order to seal the lower end of the core barrel in a fluid-tight manner. The core barrel may then be entirely removed from the drill stem with the contents under a seal and may be removed to a suitable laboratory testing apparatus where the oil and gas in the core barrel may be displaced and measured in an appropriate manner.

In the modification illustrated by Fig. 3, the core barrel is provided with a partition 25 so that an upper chamber is provided in addition to the chamber 11 with which the modification illustrated in Figs. 1 and 2 is provided. Partition 25 is provided with a central passage 27 controlled by a stopcock 28.

In the modification illustrated in Fig. 3 the core is cut and the core barrel withdrawn to the surface of the earth in the same manner as that in the modification previously described, care being taken that the drill stem contains drilling fluid in order to provide a liquid seal for the lower end of the core barrel. It is not necessary, however, to provide the upper end of the drill pipe with an enlarged section in this modification because, when the upper end of the core barrel is withdrawn to such a point as to expose stopcock 28, the stopcock may be rotated in order to close passage 27. Any gas and oil which has been released from the core as it has drawn upwardly in the drill pipe will have migrated into chamber 26 arranged above stopcock 28 so that the closing of the stopcock will

retain these fluids in the upper portion of the core barrel. The core barrel may then be removed from the hole without care being taken to preserve the fluid surrounding the core barrel. The core may then be removed for examination in the usual manner and the gas and oil displaced from the chamber 26 and measured to determine the amount of fluid which was released from the core as its pressure diminished from formation pressure to substantially atmospheric pressure.

In the modification illustrated in Fig. 4, the core barrel is provided with a partition 29 provided with passage 30 and a transparent tube 31 is arranged in the upper end of the core barrel between passage 30 and passage 16. The core barrel is provided with slots 32 to allow the transparent tube to be visible to the operator. Transparent tube 31 may be provided with suitable graduations, if desired. It is sometimes advantageous to provide passage 30 with a stopcock 28 in order to seal the transparent tube 31 independently of passage 11.

In the modification shown in Fig. 4 the core is cut and drawn upwardly in the drill stem in the manner described in the previous modifications. The gases and liquid hydrocarbons released from the core as its pressure is gradually diminished migrate upwardly and accumulate in the transparent tube 31. The drill stem is kept full of fluid so that the upper end of the core barrel may be exposed to the atmosphere, while the liquid seal is retained about the lower end of the core barrel. The amount of gas and oil accumulated in transparent tube 31 may be read off directly, while the lower end of the core barrel is still submerged in the drilling fluid in the drill pipe. After such a reading is made, the liquid and gas may be retained by closing stopcock 28 or by the use of a cap, as shown in Fig. 2, if desired, but sometimes the reading through tubing 31 is sufficient and no attempt is made to retain the fluid accumulated in tubing 31. By the use of the device illustrated in Fig. 4 relatively rapid determinations may be obtained.

The core barrels illustrated in the drawings are arranged to be held in position for taking a core by means of the pressure of the drilling fluid, but it will be evident that other means may be used for holding the barrel in position, while coring. For example, one of the known means of locking a core barrel in position is by means of a locking dog built into the core barrel as a part thereof and arranged to cooperate with a suitable mechanism with which the bit head is provided. Obviously, the core barrel herein described may be provided with such a locking means or other locking means which are known to the art or may hereafter be developed.

While I have disclosed specific modifications for carrying out the present invention, it will be apparent to a skilled worker that other means may be used for accomplishing the same or similar results. For example, while I have disclosed means suitable for use with wire lines, it will be readily apparent that the same equipment may be arranged for use in core barrels which are attached in drill stems. It is accordingly not my intention to be bound by the specific modifications disclosed, but to claim the invention as broadly as the prior art permits.

I claim:

1. A device for obtaining cores comprising, in combination, a body adapted for longitudinal

movement in a drill stem provided with a passage arranged for containing the solid mineral portion of said core open at the bottom for receiving said core, means in the lower end of said body, for retaining a core in said passage without closing the entrance to the passage, and a transparent cylinder arranged in said body having its lower end in fluid communication with said passage, and its upper end provided with a closure.

2. A device adapted for longitudinal movement in a drill stem attached to a core bit for receiving a core cut by the bit, comprising, in combination, a body defining an elongated cavity open at its lower end for receiving a core cut by the bit, means arranged in the lower portion of said body for retaining a core in the cavity without closing the opening, a passage fluidly connecting the upper end of said cavity with the exterior, means preventing the flow of fluid into the cavity through said passage and for allowing flow from the cavity to the exterior when the pressure within the cavity exceeds that in the borehole adjacent the chamber by a predetermined amount, a partition separating said cavity into an upper and a lower portion, a passage piercing said partition of a restricted size to prevent the passage of a core from the lower to the upper portion of said cavity, and a valve controlling the flow of fluid through said passage.

3. A device adapted for longitudinal movement in a drill stem attached to a core bit and for receiving a core cut by the bit comprising, in combination, a body defining an elongated cavity at its lower end for receiving a core cut by the bit, means arranged in the lower portion of said body for retaining a core in the cavity without closing the opening, a transparent member secured to said body to define a chamber above said cavity, a passage of restricted area connecting said chamber and said passage to prevent a core from passing from the cavity into said chamber, a passage connecting the upper portion of said chamber to the exterior, and a valve controlling said passage to allow the flow of fluid from the chamber to the exterior when the pressure becomes greater in the chamber than in the bore-

hole adjacent said chamber by a predetermined amount.

4. A method of coring comprising the steps of cutting a core in a borehole which contains fluid, moving said core upwardly in said borehole while maintaining it constantly under a liquid seal of fluid in the borehole, segregating and retaining gases which are released from the core as it is raised in the borehole, sealing the core and the retained gases and liquids in a gas tight manner when the core reaches the surface, and measuring the amounts of segregated liquids and gases so retained.

5. A device adapted for longitudinal movement in a drill stem attached to a core bit for receiving a core cut by the bit comprising, in combination, a body defining an elongated cavity at its lower end for receiving a core cut by the bit, means arranged in the lower portion of said body for retaining a core in the cavity without closing the opening, a passage in the upper end of said body arranged to release fluid from said cavity when the pressure in the cavity is greater than that of the liquid in which it is immersed by a predetermined amount and for retaining fluid in the upper end of the cavity when the pressure in the cavity is only slightly greater than that outside of said body, and a stopcock arranged in the lower portion of said passage.

6. A device adapted for longitudinal movement in a drill stem attached to a core bit for receiving a core cut by the bit comprising, in combination, a body defining an elongated cavity at its lower end for receiving a core cut by the bit, means arranged in the lower portion of said body for retaining a core in the cavity without closing the opening, a passage in the upper end of said body arranged to release fluid from said cavity when the pressure in the cavity is greater than that of the liquid in which it is immersed by a predetermined amount and for retaining fluid in the upper end of the cavity when the pressure in the cavity is only slightly greater than that outside of said body, and a transparent tube arranged in the upper portion of the barrel in fluid communication with said passage.

BENJAMIN W. SEWELL.
